UNITED STATES PATENT OFFICE.

JOHANNES VON DER POPPENBURG, OF CHARLOTTENBURG, NEAR BERLIN,
GERMANY.

ACCUMULATOR PLATE OR GRID.

SPECIFICATION forming part of Letters Patent No. 743,188, dated November 3, 1903.

Application filed May 13, 1903. Serial No. 156,932. (No model.)

To all whom it may concern:

Be it known that I, JOHANNES VON DER POPPENBURG, a subject of the German Emperor, and a resident of Charlottenburg, near Berlin, Germany, have invented a new and useful Improvement in the Manufacture of Accumulator Plates or Grids, of which the following is a full, clear, and exact description.

The present invention relates to the manufacture of accumulator plates or grids of that kind in which the active material, together with the current-conductor embedded in it, is inclosed by a frame made of some non-conductor of electricity, as described in my United States Patent No. 701,389. As it is impossible to effect the mechanical connection between the frame and the current-conductor solely or chiefly by the active material or paste, this connection has been effected according to the aforesaid patent by means of cross-bars of non-conducting material, which give the necessary support to the conductor in the frame.

The present invention has for its object to simplify and make cheaper the construction of accumulator-plates as compared with those of the well-known construction, while at the same time increasing their effective capacity. To this end the current-conductor is inserted in the frame itself in such manner or the frame is placed around the electric-current conductor in such manner that both form a rigid mechanical body of sufficient strength. This connection is effected by dividing the frame in accordance with the shape and size of the current-conductor or by providing it with a number of grooves, recesses, or holes, with which ribs or projections on the current-conductorengage. After the current-conductor has been placed in the frame the parts of the frame are connected or its openings, which served for the introduction of the conductor, closed with non-conducting material in such manner as to effectually prevent any contact between the current-conductor and the electrolyte, thus forcing the current to pass exclusively through the active material and utilizing it to the fullest extent for the purposes of electrochemical action. In this way special cross-bars for mechanically securing the conductor

to the frame become unnecessary and the space generally occupied by them becomes available for the active material, so that an increase of effective surface, and thus of the capacity of the electrode, is obtained. As, however, the closing of the joints of the frame parts must be done very carefully, it is necessary in carrying out this invention to take care to avoid any subdivision of the frame altogether or to make it in as few separate parts as possible.

My invention is illustrated by the accompanying drawings, in which—

Figure 1 is an elevation of a grate-shaped current-conductor of an accumulator-plate according to this invention. Fig. 2 is a section on the line A B of Fig. 1. Fig. 3 is an elevation, partly in section, of a frame with a conductor in place in it, but only partially engaging with it. Fig. 4 is a cross-section on the line C D of Fig. 3. Fig. 5 is a cross-section on the line E F of Fig. 3. Fig. 6 is a cross-section on the line G H of Fig. 3, on a larger scale, showing the active material applied on both sides of the grating. Fig. 7 is a view, partly in section, of the upper part of a modified construction according to this invention.

The current-conductor or grating *a* is shaped as shown in Figs. 1 and 2 and consists of, say, two straight longitudinal bars *b*, with a number of transverse bars *c*. The central portion of the transverse bars *c* is flat, while the ends *d*, projecting outward, are slightly curved or bent. The two lateral portions *e* of the frame *f*, made of non-conducting material—such as, for instance, vulcanized rubber—are provided on the inside with a number of recesses *g*, of which there are as many and the cross-sectional shape of which is the same as that of the ends of the transverse bars *c* of the conductor *a*. These recesses *g* are adapted to receive the free ends *d* of the transverse bars *c*.

The grating *a* is secured to the frame *f* in the following manner: The frame *f* is laid down on a flat support *h*, Figs. 4 and 5, of glass or the like, and a plate *i*, of aluminium or some other suitable material, which exactly fits in the frame, is placed in the latter, the thickness of the plate being such that the lat-

eral recesses *g* in the frame parts *e* are not covered by the plate *i*. The grating *a* is then inserted in the frame *f*, Figs. 3 and 4, the free ends *d* of the lateral arms of the transverse bars *c* being placed exactly opposite the recesses *g* in the lateral parts *e* of the frame *f*. The curved lateral arms *d* are now flattened out separately or all together, and thus straightened. Their free ends engage the recesses *g*, Fig. 5, and thus firmly secure the grating to the frame *f*. The active material is then applied to the frame thus connected with the conductor *a* in the manner shown in Fig. 6 and supported by suitable means—such as, for instance, by transverse or longitudinal bars of non-conducting material connected with the frame *f* in suitable manner. The upper part of the conductor *a*, which is arranged in two recesses in the upper part of the frame, is covered after having been introduced by the slides *s*, Fig. 3.

By connecting the conductor with the frame in the manner described the electrode is not only considerably strengthened, but also any destruction of the conductor at the ends of its cross-bars is prevented, and thus the life of the electrode is highly increased.

Of course the lateral arms *d* of the cross-bars *c* instead of being of the curved shape shown in the drawings could be of a bent shape without in any way interfering with the method of manufacture described. This bending or curving of the bars *c* can be made either when the grating is cast or after it has been cast.

This construction of accumulator-electrode can be easily modified without departing from the spirit of this invention, particularly as regards the bending and the introduction of the conductor parts into the recesses of the frame. For instance, this could take place at the points where the conductor passes through the upper part of the frame, as shown in Fig. 7. In this case the free

ends *m* of the longitudinal bars *b* are inserted into recesses *n* in the upper frame part and afterward soldered to a transverse part *v*, as shown in dotted lines in the drawings. Whether and how the active material inserted in this framed grating and completely inclosing it is subsequently covered in a suitable manner and protected against mechanical vibration, breaking off, and short circuits is immaterial to the object of the present invention.

The process can be applied both in case of positive and negative electrodes or grids.

Having thus described my invention, I claim as new and desire to secure by Letters Patent—

1. An accumulator-plate, comprising a non-conducting frame, and a conductor-grating provided with bendable arms having interlocking connection with said frame.
2. An accumulator-plate comprising a frame of non-conducting material and a conductor-grating provided with projecting arms engaging with grooves or holes on the inner side of said frame, substantially as described.
3. An accumulator-plate, comprising a frame having openings in its sides, and a metallic grating provided with bendable arms or projections which are interlocked with said openings in the sides of the frame.
4. An accumulator-plate, comprising a non-conducting frame having openings in its opposing sides, and a conductor-grating provided with bendable arms or projections which are interlocked with said openings of the frame.

In testimony whereof I have signed my name to this specification in the presence of two subscribing witnesses.

JOHANNES VON DER POPPENBURG.
